UNITED STATES PATENT OFFICE

FREDERICK WILLIAM SCHWIERS, JR., OF NEW YORK, N. Y.

APPARATUS FOR MAKING CONCRETE PILES

Original application filed February 26, 1929, Serial No. 342,873. Divided and this application filed October 22, 1929. Serial No. 401,511.

This application is a division of my co-pending application Ser. No. 342,873, filed February 26, 1929.

5 My invention relates to forming underground foundations without excavating, other than that necessary for the piles.

10 My invention more particularly relates to an apparatus for forming concrete piles in sand, mud, clay, soft earth, or similar material.

15 My invention further relates to an apparatus for positively forming a concrete pile, with a predetermined effective bearing area, which bearing area will conform exactly with the architect's specifications, avoiding variations or discrepancies between the effective bearing area of the piles, as made on the job, and as required by the architect's specifications.

20 My invention further relates to certain combinations, sub-combinations, articles of manufacture, and details of construction, all of which will be more fully hereinafter described and pointed out in the claims.

25 In the drawings I have shown one embodiment of my invention, but, of course, it is to be understood, that my invention is not to be confined to this particular embodiment shown by way of illustration.

30 In the accompanying drawings the same reference numerals refer to similar parts in the several figures.

Fig. 1 is a vertical section through a portion of a foundation, and illustrating my improved arcuate bulb excavator in operation.

35 Fig. 2 is a vertical section, on an enlarged scale, on line 2—2 of Fig. 1.

Fig. 3 is a horizontal section on line 3—3 of Fig. 1.

40 Fig. 4 is a vertical detail section on line 4—4 of Fig. 1.

Fig. 5 is a plan view.

Fig. 6 is a horizontal section, on an enlarged scale, on line 6—6 of Fig. 1.

45 Fig. 7 is a detail view of a bulb pile.

Fig. 8 is a detail view of a multiple bulb pile.

Fig. 9 is a detail of a modification.

50 Prior to my invention, it was old to use concrete piles in sand, mud, or other similar soil.

It was also old to increase the bearing area of the pile by providing it with an enlarged footing commonly called a "mushroom", by exerting pressure on the concrete in the pile shaft, so that more or less of the concrete in the pile shaft would be forced laterally into the surrounding soil before setting. It is also old in the prior art, to use explosives in the pile shaft to force, the more or less liquid concrete, into the surrounding soil, to increase 55 the area of the pile.

Others have attempted to increase the effective area of the pile by enlarging the pile shaft, employing flowing water in the shaft to cave the sand at the end of the shaft. 65

These methods all have inherent objections of their own, and, in practice, they are all alike objectionable, in that, there can be no assurance that the effective bearing area of the pile will correspond with the architect's specifications. 70

It will be clear that if the pile with its footing, pedestal, mushroom, or shelf, has not sufficient effective bearing area to carry its portion of the load of the building or other 75 structure, that it will fail, allowing the structure which it assists in supporting, either to settle or, in extreme cases, fall with possible loss of life.

For the reason that there can be no positive 80 assurance of what is the effective bearing area of such a concrete pile, provided with a footing, pedestal, shelf or mushroom, it is common practice for the architects to insist that the pile shaft be carried down to a sufficient 85 depth, so that when the concrete pile is formed, by concrete dumped into the pile shaft, the concrete pile will, itself, exclusive of any footing, pedestal, mushroom or shelf, have the required effective bearing area for 90 the particular job.

This entails digging to an excessive depth, with the consequent large additional cost of labor and material, as well as delay in the building operation. 95

By my invention these objections are avoided, because the size and shape of the pile, with its bulb, giving it, its effective bearing area, will correspond exactly with the architect's 100 specifications.

This permits of comparatively short piles to be used with economy in labor, and materials; and, also, permits the foundations to be ready for the building or other structure at an earlier date.

5 My apparatus does not require power machinery, being operated by hand and unskilled labor. Moreover, it can be used in close quarters, wherever a man can work, and
10 in locations where it would not be feasible to employ power actuating machinery.

In the drawings I have shown one form of
15 my apparatus for forming exact and predetermined concentric size bulbs on a concrete
pile, so that the effective bearing area of a
concrete pile will exactly correspond with the
architect's specifications. This will permit
20 shorter piles to be used, with the consequent
saving of labor and material, and permit the
foundations for the building structure to be
finished in the minimum time.

The pile shaft 1 is dug in the soil 2 of sand,
clay, soft dirt or similar material, in any
25 suitable manner, as by a shaft excavator of
any approved design. The shaft may be
lined with a shield (not shown) if the exigencies
of the job require it.

After the pile shaft 1 has been dug to the
depth required by the architect's specifications,
30 the excavator is withdrawn. My bulb
excavator is then brought into operative position.
As a matter of practice the depth is a little
more than required by the architect's
specification.

35 The vertical shaft 3, preferably formed of
different sections of pile secured together, is
provided with a driving point 4, Figs. 1 and
4, which is driven into the bottom of the pile
40 shaft, the fins 5, 5 preventing rotation of the
driving point.

The driving point 4 and the shaft 3 are
45 secured together, so as to permit rotation of
the shaft. This may be done in any suitable
manner, such as providing the driving point
4 with a hollow head 6 to receive the cap 7
50 screwed and also pinned on the end of the
shaft by the pin 8. The collar 9 is then
secured to the head 6 by the bolts 10, 10. I
also preferably provide the driving point 4
55 with one or more drain holes 11, 11 to permit
free passage of water from the hollow head 6.

The shaft 3 is provided with a plurality of
holes 12, 12 with which cooperate a pin 13
55 which adjustably holds a clutch collar 14, at
the predetermined elevation desired on the
shaft 3. This clutch collar 14 is provided
with two teeth 15, (only one being shown in
Fig. 1) which teeth cooperate with two slots
60 16, 16 in the toggle collar 17.

65 Pivoted to the toggle collar 17 are toggle
levers 18, 18 which in turn are pivoted to the
toggle levers 19, 19, as will be more fully hereinafter
described. These toggle levers 19, 19 are
70 pivoted to the toggle collar 20, which is
adapted to be adjusted vertically on the shaft

3 by the adjusting rod 21, which is secured to
the toggle collar 20, by means of a bolt 22,
Fig. 3. This adjusting rod 21 extends along
75 the shaft 3 and is provided with a handle 23,
to raise or lower it, to adjust the throw of the
toggle levers 18 and 19. It is held in adjusted
position by any suitable means, as by the pin
24 cooperating with the upper holes 12, 12 in
80 the shaft 3.

The toggle levers 18, 18 and 19, 19 are pivoted
85 together by the pivot pins 25, 25. On these same pivot pins 25, 25 are pivotally
mounted knife levers 26, 26 one end of the
levers being provided with cutting knives 27,
27 secured to them by any suitable means as
90 by the rivets 28, 28. The other end 29 of
each knife lever 27 is pivoted to an operating
rod 30, the upper end of which is pivotally
secured to the operating handle 31, 31 by the
pivot pin 32, 32.

95 It is clear in the mechanism so far described,
that by rocking the arms 31, 31 an
arcuate vertical movement is imparted to the
knives 27, 27 permitting them to cut, more or
less, into the wall 33 of the pile shaft 1. The
amount of each cut of the knives depends
100 upon the adjustment of the toggles 18, 18 and
19, 19; and this toggle adjustment depends on
the position of the adjustable toggle collar
20. When this collar is raised vertically as
far as permitted by the mechanism, the pivots
105 of the toggle levers 18, 18 and 19, 19 are
brought near the shaft 3, which will cause the
knives 27, 27 to lie back against the shaft in
an inoperative position, which will permit
110 their insertion in the pile shaft 1.

115 After the bulb excavator is mounted in
shaft 1, the adjusting rod 21 is moved down
until the knives 27, 27 bite into the wall 33
of the pile shaft 1, when the rod 21 is secured
120 to the shaft 3 by the adjusting pin 24. The
hand levers 31, 31 pivoted on the shaft 3 by
the pivot pin 48 are then moved vertically by
the operator, causing the knives 27, 27 to cut
125 an arcuate kerf in the soil beyond the surface
33 of the pile shaft 1. After the knives 27, 27
have completed one complete arcuate cut, at
one adjustment of the rod 21, the entire cutting
130 mechanism, including the knives and the
shaft 3 and the operating levers 31, 31, is
given a partial rotation equal to the width of
the knives 27, 27, see dotted lines 35, 35 in
Fig. 6, which represent one arcuate cut of the
135 knives. This partial rotation of the cutting
mechanism is continued, step by step, until
the knives have made a complete cut, at the
particular adjustment of the toggle levers.
The adjusting rod 21, is then pushed down
140 and secured by the pin 24 in another set of
holes 12, 12, to permit the knives 27, 27 to
still further cut into the soil until the full
bulb excavation, indicated by a dotted line
36, is completed. My bulb excavator can then
145 be withdrawn and concrete poured into the

pile shaft, forming a concrete pile 37, with a single bulb 38, Fig. 7.

Any suitable mechanism may be employed to hold the shaft 3 in proper alignment, and yet permit it, as well as the operating levers 31, 31 and rods 30, 30, to be rotated, step by step.

I have shown in Figs. 1 and 5 a cheap and simple form of carriage 39, formed by two planks 40, 40 held in spaced relation to each other by the U-shape holding members 41, 41, which are secured in any suitable manner, as by nails 42, 42 to the planks. Rollers 43, 43 are mounted on each plank, and run on a circular track 44, formed by two semi-cylindrical angle irons 45, the angle irons being mounted on two cutaway beds 46, 46; the sections of the beds being secured together by the plates 47, 47. The shaft 3 is secured to the carriage 39 in any suitable manner, as by the pin 147 passing through the shaft 3 and the holding members 41, 41.

Any loose sand or dirt 49 that is cut by the knives will fall to the bottom of the pile shaft, where it may be subsequently removed, in any suitable manner; or if sand, it may be moistened, without removing it from the shaft, and tamped prior to pouring the concrete, all depending upon the specifications of the job.

If the water level in the sand or soil is above the pile shaft, well points are inserted in the foundation and the water level lowered below the pile shaft, so that the pile shaft will be kept relatively dry during the entire operation. It is important that in a sandy foundation that the sand be damp to insure the shape of the bulb excavation and to prevent any sand crumbling or falling to break the arch formed by the knives.

If the soil is dry sand or similar material, water should be poured into the pile shaft to insure that the sand will be damp to obtain the best results. In soil such as heavy mud, clay and similar material, the use of water is not required, as these soils will stand up of their own accord. While my bulb excavator is adapted for use in all soils, I obtained the best results when it is used as above described.

In some cases I may employ a metal casing or form below the excavation for the bulb, to prevent the sand or soil caving in at that point of the pile shaft.

To make a multiple bulb concrete pile 50, such as, for example, shown in Fig. 8, it is simply necessary to adjust the clutch collar 14 at the correct location on the shaft 3, for each bulb 38 to be formed, it, of course, being understood that more than two bulbs may be formed upon a single concrete pile.

With a multiple bulb pile, the pile can be much shorter, or made smaller for a given load, or the pile can be used to carry a much greater load.

I have found in practice that a multiple

bulb pile twenty-two feet in length, formed in accordance with my invention, has the same effective bearing area as that of a straight pile thirty-two feet in depth, and the same cross-section.

I have shown in Fig. 9 another advantage of using my multiple pile. In case it is desired to later add to the load on the piles, as for example, by increasing the height of the building, or adapting the foundation to hold heavy machinery, with a pile such as 50, Fig. 9, it is merely necessary to dig down, preferably below the frost line 51 and below the upper bulb 38, and place a spread footing 52 of concrete, below the upper bulb.

This spread footing 52, therefore, obtains a grip or hold on the pile 50 which would be impossible with a plain cylindrical pile. It is, therefore, clear that by my invention the load on the piles can be increased, with little additional expense, and with no expensive equipment, and by the use of unskilled labor.

Having thus described this invention in connection with an illustrative embodiment thereof, to the details of which I do not desire to be limited, what is claimed is new and what it is desired to secure by Letters Patent is set forth in the appended claims.

What I claim is:—

1. An apparatus for excavating in a pile shaft, including a vertical rotatable shaft, toggle levers mounted on the shaft, means to mount the toggle levers at different elevations along the rotatable shaft, one or more vertically operative knives mounted on the toggle levers, and means to move the knives in a vertical plane.

2. An apparatus for excavating in a pile shaft, including a vertical rotatable shaft, toggle levers mounted on the rotatable shaft, means to adjust the radial throw of the toggle levers, means to mount the toggle levers at different elevations along the rotatable shaft, one or more vertically operative knives mounted on the toggle levers, and means to move the knives in a vertical plane.

3. An apparatus for excavating in a pile shaft, including a vertical rotatable shaft, toggle levers mounted on the shaft, means to mount the toggle levers at different elevations along the rotatable shaft, one or more vertically operative knives mounted on the toggle levers, means to move the knives in a vertical plane, and means to rotate the vertical shaft.

4. An apparatus for excavating in a pile shaft, including a vertical rotatable shaft, toggle levers mounted on the shaft, means to mount the toggle levers at different elevations along the rotatable shaft, one or more vertically operative knives mounted on the toggle levers, and a carriage adapted to rotate the vertical shaft.

5. An apparatus for excavating in a pile shaft, including a vertical rotatable shaft, a

driving point in which one end of the shaft is rotatably mounted, a carriage secured to the shaft, an operating lever pivoted on the vertical shaft, toggle levers mounted on the shaft, a cutting knife mounted on the toggle levers and adapted to move in a vertical plane, and connections between the knife and the operating lever.
